COLOSTOMY PROTECTOR

Ivy D. Fenwick, Brooklyn, N. Y.

Application August 21, 1942, Serial No. 455,632

2 Claims. (Cl. 128—283)

This invention relates to surgical appliances and more specifically to a colostomy protector.

The primary object of the invention is to provide a colostomy protector to be worn at all times and under all conditions by persons having a colostomy, and which protector is constructed and designed to be worn directly over the colostomy in contact with the wearer's body.

Another feature of the invention resides in a colostomy protector which is relatively flat and light in weight so as to be worn under a girdle, or other undergarment without an embarrassing bulge and with comfort to the wearer.

A further feature of the invention is the provision of a colostomy protector which is in sealed cushioned contact with the body of a wearer and which embodies a receptacle portion to receive any small amount of liquid which might drain from the colostomy after a colostomy irrigation, or the usual stool.

A still further feature is the provision of a colostomy protector having an air vent for the escape of any gases which might emanate from the colostomy, and which embodies a holder for a deodorant to neutralize odors of such gases.

Other features of the invention will become apparent as the following specification is read in conjunction with the accompanying drawing, in which:

Figure 1 is a perspective view of the colostomy protector, the outline of a fragmentary portion of a wearer's body being illustrated in dot and dash lines.

Figure 2 is an enlarged rear elevational view of the protector.

Figure 3 is an enlarged vertical transverse sectional view on the line 3—3 of Figure 2, showing the protector in position over a colostomy and against the body of a wearer.

Figure 4 is an enlarged horizontal sectional view on the line 4—4 of Figure 3.

Figure 5 is a sectional perspective view of the gas vent.

Referring to the drawing by reference characters, the numeral 10 designates the colostomy protector in its entirety, and which includes a relatively thin shell body 11 of ovate shape in front and rear elevation. The body 11 is preferably constructed of a light mouldable material such as Bakelite or other plastic substance. The body 11 comprises a substantially flat relatively thin front wall 12 which curves rearwardly about all of its sides as at 13. Integral with the front wall 12 is a flat rear wall 14 which has a round opening 15 therein adjacent the top thereof.

The opening 15 is of a size as to admit the passage of the colostomy A in Figure 3, and enables the flat rear wall 14 and thickened free flat edges 16 to flatly and comfortably fit against the body of a wearer at a spaced distance from the colostomy so as not to injure it. The flat rear surface of the free edges 16 and rear wall 14 are covered with a soft cushion material such as sponge rubber 17 for direct contact with the skin of the body of a wearer. The rear wall 16 being in spaced relation to the lower portion of the front wall, cooperates therewith to define a well 18 which receives any fluid or stool discharge from the colostomy A, when the protector is worn after an irrigation or after a normal stool.

The front wall of the body 11 adjacent the top thereof is provided with a vent 19 which includes an eyelet body 20 having an outer end wall provided with an arcuate shaped vent opening 21. The eyelet body 20 extends through the wall of the shell body as best illustrated in Figure 5. A rotatable closure disk 22 is mounted on the end wall of the eyelet body and has an arcuate opening 23 for partial or complete registration with the opening 21 when it is desirable to establish communication of the interior of the body 11 with the atmosphere to expel gases from the shell body. To neutralize the odors from any gases, I provide a deodorant holder in the form of confronting arcuate shaped ledges 24—24 formed integral with the rear of the front wall in the region of the vent 19. A deodorant disk 25 is inserted into and held by the ledges 24—24 for neutralizing the odors of gases before passing out through the vent 19.

Riveted as at 26 to the exterior of the front wall 12 and extending transversely thereof are spaced straps 27—27, each of which is provided with eyes 28—28 adjacent its ends. A pair of fabric belts 29—29 are looped through the eyes of the respective straps and have their ends connected by suitable fasteners or buckles 30. The fabric belts may be equipped with adjusting buckles to effect an adjustment of the belts about the waist of a wearer.

In practice, the protector 10 is applied over the colostomy A and the belts 29 applied about the body of a wearer as illustrated in Figure 1 of the drawing. The shell body 11 is relatively flat and may be worn beneath a girdle or other undergarment without causing any noticeable bulge in the outer apparel of the wearer. The protector may be thoroughly washed and cleaned to maintain the same in a sanitary condition.

Whereas the protector 10 is designed primarily for use in colostomy cases, the same will be found useful when applied over discharging wounds in lieu of dressings and bandages.

While I have shown and described what I consider to be the preferred embodiment of my invention, I wish it to be understood that such changes in construction and design as come within the scope of the appended claims may be resorted to if desired without departing from the spirit of the invention.

Having thus described the invention, what I claim as new and desire to secure by Letters Patent of the United States, is:

1. A colostomy protector comprising a rigid one-piece shell-like body of ovate shape in front elevation, said body having spaced relatively flat front and rear walls, said rear wall having an opening therein of a size to encircle a colostomy and being disposed adjacent the top of the rear 15 20

wall, the space within the body below the opening constituting a well, a soft flat resilient cushioned facing provided on the entire exterior of the rear wall for sealing engagement with the body of a wearer, the front wall having a vent opening, and means provided on the interior of the front wall adjacent said vent opening for removably supporting a deodorant element.

2. A colostomy protector comprising a rigid shell-like body having a flat rear wall and a front wall spaced from the rear wall, said rear wall having an opening therein of a size to encircle a colostomy and being disposed adjacent the top of the rear wall, the space within the body below the opening constituting a well, the front wall of the body having a vent opening adjacent the top thereof, and means provided on the interior of the front wall of the body adjacent the vent opening for supporting a deodorant element.

IVY D. FENWICK.
